(57) **CLAIM**

The ornamental design for a combined wireless otoscope ear spoon and charging storage base, as shown and described.

DESCRIPTION

FIG. 1 is a front elevational view of a combined wireless otoscope ear spoon and charging storage base showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view thereof;

FIG. 8 is another perspective view thereof;

FIG. 9 is a front elevational view in combined state; and, FIG. 10 is another front elevational view in combined state thereof.

The broken lines show portions of the combined wireless otoscope ear spoon and charging storage base that form no part of the claimed design.

1 Claim, 10 Drawing Sheets
